UNITED STATES PATENT OFFICE.

KRISTIAN PETTERSEN, OF SARPSBORG, NORWAY.

INSULATOR WITH FUSE.

Specification of Letters Patent.

Patented Apr. 22, 1913.

1,059,903.

Application filed May 2, 1912. Serial No. 694,727.

To all whom it may concern:

Be it known that I, KRISTIAN PETTERSEN, a subject of the King of Norway, residing at Sarpsborg, Norway, have invented certain new and useful Improvements in Insulators with Fuses; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to fuse-plug-insulators for electric wires and it consists in certain novel features of construction hereinafter described and claimed.

In the accompanying drawings Figure 1 20 is a vertical section of the insulator with elevation of hook and Fig. 2 is a sectional elevation of the insulator.

The body of the insulator is provided 25 with a hole *a* between collars *b* and *c* extending upward into the head of said insulator. The hole *a* as well as the hook *d* is curved between the points *e* and *f*. The hole *a* must be sufficiently large to allow for fixing (cementing) insulator to hook by 30 means of substance *h*. To secure an elastic connection between hook and cementing substance a feature of importance in places with rough climate the part of the hook to be inserted in hole *a* should be wound with 35 ribbons and soaked with shellac. Owing to the curved shape of the fixing hook a very good setting of the insulator is obtained, same neither being able to turn on the hook nor to slide off.

40 The contact ring *i* for fixing the fuse-plug to the lower part of the insulator is pro-

vided with a tongue *j*, projecting through the opening *k* and being connected with the conducting line by means of a contact screw. To secure a reliable fixing and a safe position of the contact-ring, said ring is provided with one or more projections *l* fitting into grooves *m* (or similar grooves), in the body of the insulator. To fix the contact ring the metal wedge-piece *n* is first placed 45 in position with its broadest end in, and then the square metal-piece *o* is put in place. 50

The key fixture can be carried out differently and the number of noses *l* may be 55 varied.

By my invention the following improvements are obtained: 1. The insulation is more reliable than where the insulator is carried by means of an eye-bolt clamping its body. 2. The hook is simpler and therefore also cheaper than the eyebolt mentioned above. 3. The insulator can not be turned on the hook, owing to the curved shape of same.

Claims:

1. An insulator with attached fuse plug having a hole or recess in the body of the insulator, and a hook secured in said hole, substantially as described.

2. An insulator having concentric collars 70 and having a curved hole or recess located between the collars, and a hook secured in said hole or recess, substantially as described.

In testimony that I claim the foregoing as my invention, I have signed my name in presence of two subscribing witnesses.

KRISTIAN PETTERSEN.
